PERIODICAL ABSORPTION REFRIGERATING PLANT

Sverre Johan Steensen, Ullevaal Haveby, near
Oslo, NorwayApplication May 23, 1939, Serial No. 275,309
In Norway April 30, 1937

3 Claims. (Cl. 62—5)

This invention relates to periodically operated absorption refrigerating plants in which a magazine is arranged in connection with each evaporator between the latter and the appertaining condenser, said magazine being adapted to receive during the boiling period refrigerant from the condenser and to pass vapour out from the evaporator during the evaporation period.

According to the invention apparatus is inserted between the magazine and the condenser which receives condensate during the boiling period, and as soon as the quantity of condensate has become sufficiently large, the apparatus will pass a small portion of condensate into the magazine, whereas the apparatus during the evaporation period operates as a valve which under the control of the pressure causes vapour to pass out from the magazine and from the evaporator. The valve apparatus may be made as a piston arranged in a cylinder with a small intermediate space and which carries a valve body for a valve through which condensate is passed into the magazine and vapour out from the magazine. Preferably the weight of the piston is approximately balanced by means of a spring, so that a valve needle attached to the piston is resting only with an easy tightening pressure upon its seat when the intermediate space between the piston and the cylinder is emptied of condensate, whereas this pressure is annulled by the buoyancy of the piston when the condensate has risen up to a definite height in the intermediate space, whereby condensate during the boiling period is passed in small quantities down into the magazine proper.

The invention is illustrated in the drawing. Fig. 1 shows an embodiment in vertical section through the magazine, the valve apparatus and a portion of the wall of a refrigerating box. Fig. 2 shows diagrammatically a complete plant.

Referring to the drawing there is shown in Fig. 2 a box 1 in whose interior an evaporator 2 is arranged. The evaporator is by pipes in connection with one or two magazines 7 and the latter are in turn connected through pipes 3 and condensers 4 each with a boiler-absorber K.

The valve apparatus is inserted between the magazine 7 and the appertaining pipe conduit 3 and is preferably made with an exterior cylinder 13 which may be a separate aggregate as indicated in Fig. 2, or the valve apparatus may according to Fig. 1 be made with the cylinder 13 integral with the magazine 7. The latter has an outlet 6 for the refrigerant to the evaporator 2 and a return pipe 5 for refrigerant vapour

back from the evaporator. The cylinder 13 may be enclosed in the insulation 12 of the refrigerating box in order to obtain a compact construction, but it should preferably be arranged quite outside the insulation, so that it may be cooled by the air. The cylinder 13 has at the top a cover 14 provided with a conduit 15 from the condenser. Inside the cylinder 13 a float is movable up and down with a small intermediate space. The float may be made in the form of a piston 16 with an interior bore 17 wherein a spring 18 is arranged which balances completely the weight of the piston 16. To the piston 16 is attached a needle valve 19 which is pressed against a seat 20 by means of its own weight. Between the wall of the piston 16 and the cylinder 13 there is an intermediate space 21 of about $\frac{1}{2}$ millimeter. A bore 23 with weights 22 serves for balancing the spring 18 and the piston 16.

The valve apparatus operates as follows:

At the commencement of a boiling period the magazine 7 is empty, and the same applies to the apparatus and the conduit 15. As soon as the boiling commences, the vapour passes from the absorber through the condenser and the conduit 15 into the apparatus and stops there, because the needle 19 engages its seat 20. The pressure increases thereby in the space 21 until the condensation pressure is obtained. The vapour will then be condensed in the condenser 30 and pass through the conduit 15 into the space 21 between cylinder 13 and piston 16, so as to be collected therein. When the liquid level in space 21 has become sufficiently high, the buoyancy of the piston 16 is so large as to overcome 35 the tightening pressure of needle 19 on seat 20, and the piston 16 is then lifted. Thereby the valve opens and the condensate flows down into the magazine 7, whereupon the needle 19 again moves down upon its seat 20. Into the magazine 40 there has now arrived about three to five grams of condensate. This is repeated during the whole boiling period until all condensate, for instance 500 g., has passed into the magazine which is then filled.

After the boiling period the pressure in the condenser conduit 15 of the absorber and in the valve apparatus sinks, whereupon the condensate in the evaporator with appertaining magazine 7 evaporates gradually and passes the same way 50 back into the absorber, the vapours requiring only a small over-pressure in order to lift the valve needle 19.

I claim:

1. Periodical absorption refrigerating plant, 55

comprising a boiler absorber, a magazine, a condenser, a connection between the magazine and the condenser, apparatus inserted between the magazine and the condenser and adapted to receive during the boiling period condensate and to pass, at any time the quantity of condensate has become sufficiently large, a small portion of the condensate into the magazine, and means whereby the apparatus during the evaporation period operates as a valve which under control of the pressure passes vapour out from the magazine or from the evaporator.

2. Arrangement according to claim 1, characterised in that the apparatus between the magazine and the condenser is made as a piston which is arranged in a cylinder with a small intermediate space and carries a valve body for a valve through which condensate is passed into the magazine and vapour out from same.

3. Arrangement according to claim 1, charac-

terised in that the apparatus between the magazine and the condenser is made as a piston which is arranged in a cylinder with a small intermediate space and carries a valve body for a valve through which condensate is passed into the magazine and vapour out from same, the weight of the piston being nearly or completely balanced by means of a spring, so that a valve needle attached to the piston rests only with a small 5 tightening pressure on its seat when the intermediate space between the piston and the cylinder is emptied for condensate, whereas this pressure is annulled by the buoyancy of the piston when the condensate has risen up to a definite 10 height in this intermediate space, whereby the condensate during the boiling period is passed in small quantities down into the magazine proper.
